United States Patent Office

Des. 211,889

Patented Aug. 6, 1968

211,889

TOY FIGURE

Josephine Lazzarini Battiala, 2531 Woodhull Ave.,
Bronx, N.Y. 10469

Filed Nov. 13, 1967, Ser. No. 9,358

Term of patent 3½ years

(Cl. D34—4)

I claim:

The ornamental design for a toy figure, substantially as shown.
